UNITED STATES PATENT OFFICE.

PAUL H. LANGE, OF BRIDGEPORT, CONNECTICUT, ASSIGNOR TO THE MAX AMS MACHINE COMPANY, OF BRIDGEPORT, CONNECTICUT, A CORPORATION OF NEW YORK.

HORN-SUPPORTING MEANS.

Application filed October 20, 1925. Serial No. 63,801.

This invention relates to machines, such as body-forming machines, in which bodies embracing a horn must be passed out of the machine; and the main object and feature 5 of the invention is to provide such supporting means for the free end of the horn as will admit of the bodies passing out of the machine and out of engagement with the horn without interfering with the supporting means.

In the accompanying drawings the invention is disclosed in a concrete and preferred form in which:

Fig. 1 is a plan view of a portion of a horn 15 at the out-feed end thereof and adjacent mechanism for supporting the free end of the horn embodying the invention:

Fig. 2 is a vertical transverse sectional view in the plane of line 2—2 of Fig. 1; and 20 Fig. 3 is a view looking in the direction of arrow 3 of Fig. 2.

1 indicates a horn of any suitable construction, the free end of which must be supported while bodies pass out of engagement therewith. Any suitable means such as conveyor 2 having dogs 3 may be used for passing bodies 4 in spaced relation over said horn and eventually out of engagement therewith. Adjacent the out-feed end of the 25 horn is a rotatable carrier 5 provided with a number of horn-engaging members, here taking the form of rollers 6. This carrier is here in the form of a disk mounted on a vertical axis 7 adjacent the horn and so 30 arranged that it projects part-way beneath the horn to thereby bring successive horn-engaging members in contact with the lower surface of the horn at points between the bodies passing over the horn; and it will be 35 seen that before one member 6 moves out of contact with the horn another member will have been brought into position to sustain it. It will be observed that the spacing of members 6 bears a definite relation to 40 the position of dogs 3 on chain 2; and, also, that the speed of rotation of carrier 5 is such that member 6, while in engagement with the horn, moves substantially at the

same speed as the bodies passing thereover so that there is no interference between the 50 bodies and the sustaining means for the horn.

Any suitable means may, of course, be employed to actuate the parts but as here shown vertical shaft 7 carries a bevel gear 8 meshing with bevel pinion 9 on shaft 10; and this shaft carries a spur gear 11 that meshes with pinion 12 on shaft 13. Shaft 13 may receive its motion in any suitable way as by means of sprocket 14 over which passes a chain 15 55 trained over sprocket 16 on shaft 17; and such shaft 17 carries a bevel gear 18 that engages with a corresponding gear 19 on shaft 20 which is also provided with a bevel gear 21 that meshes with bevel gear 22 on 60 vertical shaft 23 having a sprocket 24 over which passes chain 2. 25 is another vertical shaft having a sprocket 26 over which chain 2 is likewise trained; but this shaft, as well as others to complete the transmission 65 means for chain 2, may be an idler. It will be seen, however, that there is a definite relation between the speed of the bodies and the speed of rotation of carrier 5.

In order to assist in sustaining the weight 75 of the horn there is a bracket 27 having a roller 28 beneath carrier 5 and over which it rolls in line with the horn so that the weight of the horn is transmitted to stationary bracket 27.

I claim:

The combination with a horn, of means for supporting the free end thereof including: a rotatable member mounted on a vertical axis and extending part way beneath the horn, horn-engaging members in spaced relation on said rotatable member to successively engage and support the horn, and a stationary member to support the rotatable member at the point where the latter passes 85 beneath the horn.

Signed at Bridgeport, in the county of Fairfield, and State of Connecticut, this 16th day of September, 1925.

PAUL H. LANGE.
